(57) **CLAIM**

The ornamental design for a folding electric personal utility scooter, as shown and described.

DESCRIPTION

FIG. 1 is a perspective view of a folding electric personal utility scooter, showing our new design in a sitting configuration;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a perspective view thereof, illustrated in a folded configuration;

FIG. 9 is a front elevational view of FIG. 8;

FIG. 10 is a rear elevational view of FIG. 8;

FIG. 11 is a left-side elevational view of FIG. 8;

FIG. 12 is a right-side elevational view of FIG. 8;

FIG. 13 is a top plan view of FIG. 8; and,

FIG. 14 is a perspective view thereof, illustrated in a standing configuration with a seat removed.

The broken lines in FIGS. 1-7 depict portions of the folding electric personal utility scooter that form no part of the claimed design.

1 Claim, 12 Drawing Sheets
